UNITED STATES PATENT OFFICE

149,968

DESIGN FOR A MOTOR BIKE

Lawrence C. Oertle, Milwaukee, and Theodore
Rostan, Hales Corners, Wis.

Application September 5, 1946, Serial No. 133,086

Term of patent 14 years

(Cl. D90—8)

To all whom it may concern:

Be it known that we, Lawrence C. Oertle and Theodore Rostan, citizens of the United States of America and residents of Milwaukee and of Hales Corners, town of Franklin, respectively, in the county of Milwaukee and State of Wisconsin, have invented a new, original, and ornamental Design for a Motor Bike, of which the following is a specification, reference being had to the accompanying drawings, forming a part thereof.

In the drawings:

Fig. 1 is a perspective view of the motor bike showing our new design.

Fig. 2 is an elevational view of the right hand side of the motor bike; and

Fig. 3 is an elevational view of the left hand side of the motor bike.

We claim:

The ornamental design for a motor bike, as shown.

LAWRENCE C. OERTLE,
THEODORE ROSTAN.
